CLAIM

The ornamental design for a light holder, as shown and described.

DESCRIPTION

FIG. 1 is a perspective view of a light holder showing our new design;

FIG. 2 is a top plan view thereof;

FIG. 3 is a front elevational view thereof;

FIG. 4 is a right side elevational view thereof;

FIG. 5 is a left side elevational view thereof; and

FIG. 6 is a rear elevational view thereof.

The broken line showing of a cylindrical unit with hooks in FIG. 1 is for illustrative purposes only and forms no part of the claimed design.
